COMBINATION PROTECTIVE SHIELD AND
ACCESSORIES ACCOMMODATION BIB

George D. Brown, West Los Angeles, Calif.

Application January 21, 1944, Serial No. 519,222

1 Claim. (Cl. 2—50)

This invention, as generally comprehended in the preceding title relates to a novel cape-like shield fashioned to embody as an integral part thereof a complementary bib, the latter being provided with a plurality of selectively usable pockets, the latter to conveniently hold various accessories, such as curlers, combs and the like, whereby to provide a double utility article helpful in beauty salons and the like during the procedure of giving a so-called "cold wave" permanent.

The use of shields, shawls and aprons in barber shops, beauty salons and equivalent establishments is, of course, not new. On the other hand, the provision of an especially designed cape-like shield serving as a water resisting and repelling shoulder covering, and including a pocketed bib constitutes, it is believed, a unique article in that by having the various needed accessories, such as curlers, combs, tension eliminators and the like handily and conveniently arranged for the attendant constitute a novel contribution to this line of endeavor.

In carrying out the principles of the invention I have evolved and produced a simple, economical and an otherwise desirable article which is appropriate for the intended purposes, aptly constructed for expedient use, and mutually advantageous to the patron and attendant.

Other features and advantages will become more readily apparent from the following description and the accompanying illustrative drawings.

In the drawings, wherein like numerals are employed to designate like parts throughout the same:

Figure 1 is a perspective view of the combination shield and bib showing one way in which it may be worn by the patron, the same being pictured in a frontal position but normally occupying a hanging position either to the rear or selectively over either left or right shoulder.

Figure 2 is a top plan view, to bring out the configuration and relative coaction of component parts.

Figure 3 is an enlarged vertical sectional view taken along the line 3—3 of Figure 2.

Figure 4 is a fragmentary horizontal sectional view on an enlarged scale taken along the line 4—4 of Figure 3.

Referring now to the drawings by distinguishing reference numerals, it will be observed that the principal structure is actually made up of three pieces of material, namely, a body portion and a pair of patches appropriately patterned and stitched in superimposed positions thereon.

Taking the main or body portion this is of suitable water-repelling and resisting sheet material, such as for example, that which is employed in making of shower curtains and it includes what 5 may be conveniently identified as a shawl or shield portion 5 having a reduced, that is, narrowed pendant portion 6 which I shall describe as the pendant bib. At this point it may be mentioned that all of the parts are properly finished 10 around their marginal edges with appropriate binding cloth or material as at 7. It is unnecessary, however, to follow the contours or lines of the marginal bindings, these being evident from the drawings and of no particular functional 15 moment except for strength and appearance. The body portion 5 has a circular neck embracing opening or hole 8 and a registering V-shaped slot 9 communicating therewith, thus providing the desired yoke-like construction to permit the 20 device to be placed around the neck and over the shoulders. It is held in place by companion tapes or ties 10.

A substantially segmental patch or extra piece of material 11 has its lower curvate edge stitched, 25 as at 12, to the underlying body sheet, the stitching occurring somewhat at the junctural portions of the body and bib. The left hand end is stitched completely across and the right hand end is partly stitched down at the points 13 and 14. Additional rows of stitching at somewhat 30 radial or longitudinally spaced points, as at 15 and 16, serve to define a main central relatively large pouch 17 and a pair of end pockets 18 and 19. The pocket 19 is provided with openings at 35 the points 20 and 21 and lends itself highly adaptable for the accommodation of wool crepe, the crepe projecting through the relatively narrow mouthed pockets 20 and 21 so that it can be picked out in small wads. The main pouch 17 serves as a pocket for large curlers (not shown). The pocket 18 can serve to accommodate combs. The small pocket 22 indicated by dotted lines 40 comes in handy to accommodate one or more tension eliminators or other small articles used by operators in a beauty parlor.

The somewhat shorter patch of material, the third piece, is denoted by the numeral 23 and this is stitched around its lower and end edges to correspondingly contoured edge portions of the main body. This patch is preferably divided centrally 50 by a line of stitching 24 into somewhat duplicate pockets 25 and 26, the pocket 25 being for medium curlers and the pocket 26, if desired, for midget curlers. There is surplus of material in the part 55

23 and this is formed into expandible and contractible pleats 27.

As indicated, this is a time saver shield and bib and when commencing the operation of giving the "cold water" wave it is strapped on and tied so that it hangs down over the back of the patron. Then as the sides of the hair are waved it is shifted from right to left or from left to right to bring the pocket convenient in position over the arms or shoulders of the wearer. Consequently, it serves not only as a protective yoke or shield but also as a practical and convenient ways and means of placing at the finger tips the various articles and accessories needed by the operator performing the operation.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

A combination protective shield and accessories accommodating bib to be worn by a patron in a beauty salon comprising a body formed from a

sheet of water-repellant material, said body being of substantially elliptical shape with its greatest dimension extending horizontally, but having its lower portion extended downwardly midway its width to form a depending bib of appreciably less width than the body, the upper portion of said body being formed midway its width with a neck opening having an entrance slot leading therefrom, tapes at opposite sides of the inner end of the entrance slot adapted to be tied together and removably secure the shield about a person's neck in covering relation to the upper portion of the person's body, the depth of the body and its bib being such that the bib terminates well above a person's waist, a sheet of water-repellant material secured along its ends and lower edge to side edges and the lower edge of said bib, and free along its upper edge and forming a pocket open along its top, and a strip of 20 water-repellant material extending across the lower portion of the body and stitched along its lower edge one end, and at one end of its upper edge, and free along one end and its upper edge, and lines of stiches passing through the strip 25 and the body in spaced relation to the ends of the strip and forming an intermediate pocket over the bib open at its upper end and other pockets of end portions of the bib, one of which is open along its upper end and its outer side.

30 GEORGE D. BROWN.
